(57) **CLAIM**

The ornamental design for a power cord, as shown and described.

DESCRIPTION

FIG. 1 is a front perspective view of a power cord showing our new design;

FIG. 2 is a top plan view thereof;

FIG. 3 is a bottom plan view thereof;

FIG. 4 is a right side elevational view thereof, the left side elevational view being a mirror image thereof;

FIG. 5 is a front elevational view thereof shown in an enlarged scale for clarity; and,

FIG. 6 is a rear elevational view thereof.

The broken lines showing portions of the plugs on the ends of the power cord in FIGS. 1-6 form no part of the claimed design.
